(57) **CLAIM**

The ornamental design for an external fixation clamp for medical procedures, as shown and described.

DESCRIPTION

FIG. 1 is a side and top view of an external fixation clamp for medical procedures; and,
FIG. 2 is a top view, the rear view being identical.

The broken lines in the drawings are included for the purpose of illustrating portions and environmental elements of the external fixation clamp for medical procedures and form no part of the claimed design.

1 Claim, 2 Drawing Sheets
